CLAIM

We claim the ornamental design for a bottle, as shown and described.

DESCRIPTION

FIG. 1 is a top perspective view of a bottle showing our new design;

FIG. 2 is a front view of the bottle of FIG. 1;

FIG. 3 is a rear view of the bottle of FIG. 1;

FIG. 4 is a right side elevation view of the bottle of FIG. 1;

FIG. 5 is a left side elevation view of the bottle of FIG. 1; and,

FIG. 6 is a bottom plan view of the bottle of FIG. 1.

The portions of the bottle and the environment shown in broken lines form no part of the claimed design. With respect to FIG. 6, a raised portion of the bottle near a center of the bottle is represented in solid lines. The solid lines of the raised portion illustrate a change in width of the raised portion as it decreases in width in a direction extending toward a top of the bottle. The solid lines also illustrate rounded top corners of the raised portion of the bottle as can also be seen in FIGS. 1–5.
